BOBBIN HOLDER

William H. Bahan, Greenville, S. C.

Application January 7, 1937, Serial No. 119,486

5 Claims. (Cl. 139—249)

This invention relates to means for holding the lowermost filling carrier or bobbin in a magazine loom so as to prevent its rotation or oscillation prior to being transferred into the shuttle 5 of the loom.

In magazine looms, filling carriers are placed in a rotating hopper sometimes called a battery and the ends from the carriers are wound around the axis on which the hopper plates are mounted 10 so as to provide an end which can be used by the thread grippers for gripping the ends when the filling carrier is transferred into the shuttle upon the exhaustion of the filling on the preceding carrier.

15 It has been experienced heretofore that vibration in the loom causes rotation or oscillation of the lowermost filling carrier in the magazine loom prior to its transfer to the shuttle, and the end of the thread extending therefrom will become broken so that when the filling carrier is transferred into the shuttle, the end will not be engaged by the thread gripper; consequently, the filling will not be left in the warp and a mis-pick or thin place in the cloth will occur.

20 It is therefore, an object of this invention to provide means for holding the lowermost filling carrier or bobbin in a magazine prior to its transfer into the shuttle of the loom, so that the filling carrier cannot oscillate or rotate prior to its 25 transfer into the shuttle.

25 It is a further object of this invention to provide a bobbin support for normally engaging the lowermost filling carrier in a loom magazine, said support being carried by the transfer arm of the loom and being automatically operable thereby to relieve said pressure upon bobbins upon the actuation of the transfer arm to transfer the filling carrier into the shuttle.

30 Some of the objects of the invention having been stated, other objects will appear as the description proceeds, when taken in connection with the accompanying drawings, in which:—

35 Figure 1 is a transverse sectional view through the battery and lay of a magazine loom, showing the invention applied thereto;

40 Figure 2 is a sectional plan view taken along line 2—2 in Figure 1 showing the lay disposed directly therebeneath in a position for receiving a bobbin or filling carrier of a magazine;

45 Figure 3 is an elevation taken along line 3—3 in Figure 1.

50 Figure 4 is a transverse sectional view through a loom similar to that shown in Figure 1 but

showing a modified form of a bobbin support secured thereto;

5 Figure 5 is a sectional plan view taken along line 5—5 in Figure 4 showing the lay therebeneath in bold lines;

Figure 6 is an elevation taken along line 6—6 in Figure 4;

10 Figure 7 is an isometric view of one end of the bobbin engaging means showing the serrations in the engaging face thereof.

15 Referring more specifically to the drawings, the numeral 10 denotes a conventional hopper stand for a battery loom which has rotatably mounted therein hopper plates 11 and 12 which are spaced from each other for supporting the filling carriers 14. As heretofore stated when a filling carrier 14 reaches its lowermost position where it is to be transferred into the shuttle there is a tendency for the filling carrier to oscillate or rotate, thereby breaking the ends of the yarn and causing a mis-pick in the cloth which is being woven. It is, therefore, necessary to provide a supporting means for normally exerting a pressure against the lowermost bobbin to stabilize the same to prevent this vibration. In order to accomplish this result, I have provided a bobbin support 15 which has a resilient tip portion 16 for normally engaging the filling on the lowermost filling carrier 14. The other end of member 15 is rotatably mounted upon pin 17, which pin is 20 rotatably mounted in the lower end of leg 19 of transfer member 20. A suitable dog 21 is fixedly secured as at 22 to the pin 17 and is adapted to be normally held in the bold line position as shown in Figure 1 by means of torsion spring 24, 25 said torsion spring having one end thereof normally secured to collar 17a which is integral with pin 17 and the other end of said spring being secured around the transfer leg 19. It is evident 30 that the torsional stress exerted by this spring will tend to rotate the dog 21 in a clockwise manner. The member 15 is slidably supported, intermediate its ends by means of an eye bolt 26 which projects outwardly from the base of hopper stand 35 10. This pin has an eyelet in the end thereof which slidably confines the intermediate portion of member 15. The transfer member 20 has a laterally extending arm 27 which is adapted to engage the filling carrier 14 when a transfer is 40 made.

45 In the normal operation of the loom, lay 29 oscillates back and forth and at the same time the shuttle 30 traverses the loom, back and forth, to cause the filling upon filling carriers 14 to be 50 made.

55 Figure 5 is a transverse sectional view through a loom similar to that shown in Figure 1 but

placed in the warp. Upon the exhaustion of yarn upon the filling carrier 14, which is in shuttle 30, suitable conventional mechanism will be thrown into operation to cause the transfer member 20 to assume the dotted line position as shown in Figure 1. At the same time, the lay of the loom will be in dotted line position and also the dog 21 will be caused to rotate to its dotted line position. In other words, the bunter 31, which is secured to lay 29, will engage dog 21 to rotate the transfer member 20 to the dotted line position which will cause the filling carrier 14 to be transferred into the shuttle 30. It will also be noted that shortly prior to the transfer the bobbin support 15 will be withdrawn from the lowermost filling carrier simultaneously with the movement of arm 27 thereby allowing transfer arm 27 to transfer the lowermost bobbin without any obstruction. Immediately after the transfer, the hopper plates 11 and 12 rotate until the next bobbin assumes the lowermost position previously occupied by the bobbin transferred, and the members will again assume their bold line position at which time the bobbin support will be engaging the yarn on the lowermost bobbin.

The transfer arm 27 is normally held in raised position as shown in bold lines in Figure 1 by means of conventional torsion spring 20a. This spring also holds member 16 against the yarn on the lowermost bobbin.

It is therefore, seen that I have provided means for supporting the lowermost bobbin in a magazine loom, said means being carried and operated by the transfer arm so that the bobbin support will not interfere with the transfer operation.

Figures 4 to 7 inclusive, show a slightly modified form of a bobbin support which is adapted to be secured in a similar manner to that shown in the preceding form, except that the holding means for the support is normally carried by the transfer arm pivot 20b. In this form the downwardly extending leg 19 of transfer arm 20 has pivotally secured thereto a bolt 17 which, in turn, supports the dog 21. The bolt 17 also rotatably supports a washer member 35, to which is integrally secured a threaded rod portion 36, said rod portion being threadably secured in a slotted member 37. The free end of slotted member 37 has a T-shaped arcuate member 38 integral therewith which member has serrations 39 in its face for engaging the yarn on the lowermost bobbin 14. The intermediate portion of member 37 has a longitudinal slot 40 therein which is penetrated by stationary pin 41. This pin extends laterally from the free end of arm 42, which arm 42 is secured to transfer arm pivot 20b by any suitable means such as set screw 43.

It will be noted that by mounting of bracket 42 in the manner shown, it is possible to rotate the free end of the bracket and its associated pin 41 to the desired position and then fix it in position by means of set screw 43. This will allow adjustment of the angle of approach of portion 38 on the free end of member 37, relative to the yarn, and thereby insure that the lowermost bobbin 14 will be properly engaged at the proper time. Also by providing the threaded portion 36, the overall length of the bobbin support can be regulated. That is, if the serrated face 39 projects to the right too far, the necessary adjustment or shortening of this member may be obtained by removing member 37 and screwing it to the left on the threaded portion 36. It is

therefore, seen that the necessary adjustment of the bobbin support can be obtained in this form of the invention.

Likewise, in this form, the lay of the loom as well as the transfer mechanism is shown in dotted line position as well as in bold line position. This is done to illustrate the position the parts will assume when the transfer of the lowermost bobbin 14 is made. The transfer is made and the bobbin is supported in a very similar manner to the forms shown in Figures 1 to 3 inclusive, and the transfer position of the parts is shown in dotted line.

The rod or shaft 20b on which the transfer arm is pivoted, is fixedly mounted at one end in 15 the hopper stand by means of a set screw 20c.

In the drawings and specification there has been set forth a preferred embodiment of the invention, and although specific terms are employed, they are used in a generic and descriptive sense only, and not for purposes of limitation, the scope of the invention being set forth in the appended claims.

I claim:

1. In a loom having a rotary hopper for holding a plurality of filling carriers and having a lay for confining a shuttle and having a transfer mechanism including a transfer arm for transferring the lowermost filling carrier from the hopper to the shuttle upon exhaustion of the filling on the carrier in the shuttle, said transfer arm having a downwardly projecting arm integral therewith and being disposed at approximately right angles thereto, a member having one end pivotally connected to the lower end of said downwardly projecting member and having a member on the other end thereof for engaging the filling on the lowermost filling carrier and fixed means for slidably supporting said latter member intermediate its ends. 40

2. In a battery loom having a rotary hopper for holding bobbins, a lay carrying a shuttle, a transfer arm operable upon exhaustion of the filling on the bobbin in the shuttle for moving the lowermost bobbin in the hopper into the shuttle, said transfer arm having a downwardly projecting arm movable therewith and being disposed at approximately right angles to the transfer arm, a member pivotally mounted on said downwardly projecting arm and having a member on its other end for engaging the yarn on the lowermost bobbin in the hopper when the transfer arm is normally raised to inoperative position and being movable along with the transfer arm out of contact with the yarn on said bobbin as the transfer arm is swung in a transfer operation, and fixed means slidably supporting an intermediate portion of said member pivotally mounted on said downwardly projecting arm. 60

3. In a loom having a rotary hopper for holding a plurality of filling carriers and having a lay for confining a shuttle and having a transfer mechanism including a pivotally mounted transfer arm for transferring the lowermost filling carrier from the hopper to the shuttle upon exhaustion of the filling on the carrier in the shuttle, a transfer pivot for pivotally supporting said transfer arm, said transfer arm having a downwardly projecting arm integral therewith and being disposed at approximately right angles thereto, a member having one end pivotally connected to the lower end of said downwardly projecting member and having its other end engaging the filling on the lowermost filling carrier 75

and fixed means supported by said transfer pivot for slidably supporting said yarn engaging member intermediate its ends.

4. In a battery loom having a hopper stand in which a rotary battery for holding a plurality of yarn carrying bobbins are mounted for delivery one at a time to the shuttle of the loom, said loom having a transfer arm provided with a horizontally disposed portion whose tip is adapted to engage the lowermost bobbin and transfer it into the shuttle of the loom and also having a downwardly depending arm, means for engaging the yarn on the lowermost bobbin for preventing the vibrations of the loom from imparting rotary motion to said lowermost bobbin comprising a bobbin holding member slotted intermediate its end and having one end pivotally secured to the lower end of said downwardly depending arm and having an enlarged portion on its other end for engaging the yarn on said lowermost bobbin, a fixed shaft on which the transfer arm is mounted for pivotal movement at the junction point of the horizontal portion and the downwardly depending portion, and a support secured to said shaft and having means on its other end for entering said slot in said bobbin holding member for slidably supporting

the same for movement towards and away from the lowermost bobbin upon operation of the transfer arm.

5. In a loom having a hopper frame and a rotary hopper mounted therein for holding a plurality of yarn carrying bobbins and having a transfer arm operable at times to transfer the lowermost bobbin in the rotary hopper into the shuttle of the loom, said transfer arm having a downwardly depending portion, a fixed shaft on which the transfer arm is mounted for pivotal movement, a member carried by the lower end of said downwardly depending member and projecting towards the lowermost bobbin for engaging the yarn on the same to prevent rotation of the lowermost bobbin due to the vibrations in the loom, a support carried by the hopper frame and slidably engaging said member carried by the lower end of the transfer arm for supporting and guiding the same during a transfer operation and whereby the member carried by the downwardly depending member will normally engage the lowermost bobbin in the rotary hopper and will move laterally away from the lowermost bobbin upon actuation of the transfer arm.

WILLIAM H. BAHAN.
